SAFETY VALVE

William A. Jones, Westerleigh, Staten Island, N. Y., assignor to The Babcock & Wilcox Company, Bayonne, N. J., a corporation of New Jersey

Application October 25, 1928, Serial No. 314,868

11 Claims. (Cl. 137—53)

This invention relates to a safety valve for a steam boiler that is provided with a superheater for the steam. In such boilers there is a drop in pressure between the saturated steam in the boiler drum and the superheated steam passing out of the superheater due to the friction in the superheater. By the present invention a superheated steam safety valve is actuated by a motive fluid controlled by the operation of a relief valve responsive to the saturated steam pressure in the boiler.

The invention will be understood from the description in connection with the accompanying drawing in which Fig. 1 is a vertical section through an illustrative embodiment of the invention, and Fig. 2 is a section along the line 2—2 of Fig. 1. In the drawing reference character 1 indicates an inlet into a valve casing which inlet is connected to the superheated steam space of the boiler. A waste steam outlet leading to the atmosphere is indicated at 2. A valve seat 3 may be screwed into place inside the casing as indicated at 3', and a valve disc 4 is seated upon the same. The valve disc 4 is provided with a stem 5 that passes through a guide 6 which guide may be made integral with the valve seat 3. A piston 7 is attached to the lower end of the valve stem 5, for example, by screwing the same to the threaded end 7' of the valve stem 5. The piston 7 fits in a cylinder 8 inside the casing, and an opening or bleeding orifice 9 is provided through the side wall of the cylinder. An opening 10 leads through the casing into the lower end of the cylinder 8 and a pipe 11 connects the opening 10 to the outlet side of a saturated steam safety valve *a* on the boiler.

A closure 12 is provided at the upper end of the valve casing and carries a central projection 13 that operates as a stop to limit the extent of travel of the valve disc 4. The space 14 is connected to the inlet 1 and extends above the valve disc 4. This space is therefore at all times filled with superheated steam.

The operation is as follows: Steam from the superheater passes through the inlet 1 and surrounds the valve disc 4, thus pressing this disc in place against its seat 3. When the saturated steam safety valve *a* opens the steam therefrom passes through the pipe 11 and opening 10 into the cylinder 8, thus raising the piston 7 and lifting the valve disc 4 from its seat 3, and thereby permitting escape of superheated steam to the atmosphere. Due to the fact that the saturated steam pressure is greater than the superheated steam pressure because there is a pressure drop

through the superheater, the pressure of the saturated steam in the cylinder 8 will lift the valve disc 4 against the superheated steam pressure when the effective areas of the piston 7 and the valve disc 4 are equal to each other. It is preferable, however, to make the area of the piston 7 somewhat greater than the area of the valve disc 4 to make it certain that the saturated steam pressure will open the valve against the pressure of the superheated steam and overcome the weight of the valve as well as the friction. The projection 13 limits the distance to which the valve disc 4 can be lifted. The point at which the projection 13 stops the disc 4 is such that the lower edge of the piston 7 will uncover the bleeding orifice 9 and permit saturated steam to pass out gradually. When a sufficient amount of superheated steam has escaped to lower the saturated steam pressure to the point where it is safe the saturated steam safety valve which discharges into inlet 11 closes. The entrapped saturated steam in the cylinder 8 escaping through the bleeding hole 9 lowers the pressure in the cylinder sufficiently to cause gravity, together with the pressure of the superheated steam, to close the valve disc 4 against its seat 3. The superheat escape of superheated steam is thus shut off and since the saturated safety valve had already closed, no more steam will escape from the boiler.

I claim:

1. In a safety valve for a steam system containing superheated and saturated steam, means subjected to the operating influence of saturated steam only when such saturated steam is at a predetermined pressure for exhausting the superheated steam from said system, and means to permit cutting off the exhaust of the superheated steam when the pressure of the saturated steam has fallen below said predetermined limit, said last named means including an orifice permitting the exhaust of saturated steam while the valve remains open.

2. In a safety valve for a steam boiler, means to utilize the difference in pressure between superheated and saturated steam to operate said valve and exhaust superheated steam when the pressure of said saturated steam exceeds a predetermined limit, said means including a pair of valve discs connected by a valve stem with said discs acted upon by the saturated steam and superheated steam respectively in opposition to each other.

3. In a safety valve for a steam boiler that produces saturated steam and superheated steam, a valve disc connected by a steam to a second

CERTIFICATE OF CORRECTION.

Patent No. 1,970,937.

August 21, 1934.

WILLIAM A. JONES.

It is hereby certified that error appears in the printed specification of the above numbered patent requiring correction as follows: Page 1, line 81, strike out the word "superheat"; and line 110, claim 3, for "steam" read stem; and that the said Letters Patent should be read with these corrections therein that the same may conform to the record of the case in the Patent Office.

Signed and sealed this 5th day of March, A. D. 1935.
